FOOD COMMINUTOR OR SIMILAR ARTICLE

Samuel J. Popeil, 2920 N. Commonwealth,
Chicago, Ill. 60657

Filed Nov. 26, 1965, Ser. No. 88,241

Term of patent 14 years

(Cl. D89—1)

FIG. 1 is a front perspective view of the food comminutor or similar article showing my new design;

FIG. 2 is a front elevational view;

FIG. 3 is a rear elevational view;

FIG. 4 is a side elevational view; and

FIG. 5 is a top plan view.

The dominant features of the design are shown in full lines.

I claim:

The ornamental design for a food comminutor or similar article, as shown and described.
